FUR CURLING DEVICE

Samuel G. Shapiro, Philadelphia, Pa.

Application February 26, 1948, Serial No. 11,040

3 Claims. (Cl. 69—20)

1

The present invention relates to devices for curling or changing the character of curls on fur pelts of the Persian lamb type, for example.

Heretofore, as a hand tool, a heated die presenting a plurality of curling edges of various contours determining a flat surface, was applied with more or less pressure against the hair side of a pelt and let rest thereon awhile, or else upon contact with the pelt, the die was given a slight arcual movement and let rest a while. Only points of the hairs were ever in actual contact with the die curling edges and considerable pressure was necessary to be exerted by the operator so that the entire surface covered by the die should be properly acted on.

It is therefore an object of this invention to provide a novel and improved curling tool of the type described, which permits the curling edges of the die to act progressively along the length of the hairs coming into contact with them, and for proper working requires that pressure be on a lane which is a comparatively small part of the total die surface, so that the operator does not tire so easily and whereby the curling is more effective than heretofore possible, because more than merely a point or so of the individual hairs are contacted and acted upon by the die.

Another object hereof is to provide a curling tool for use on furs, of novel and improved construction, including a die made up of interchangeable parts so that the design character of the composite die may be altered.

A further object of this invention is to provide a novel and improved curling tool of the character mentioned, which is easy and convenient to use, reasonable in cost and efficient in carrying out the purposes for which it is designed.

Other objects and advantages will become apparent as this disclosure proceeds.

In the accompanying drawings forming part of this specification, similar characters of reference indicate corresponding parts in all the views.

Fig. 1 is a front view of a fur curling tool embodying the teachings of this invention.

Fig. 2 shows the die member as it appears in assembly in Fig. 1.

Fig. 3 shows the face of the die. This is a bottom view of either Fig. 1 or Fig. 2.

Fig. 4 is a section taken at line 4—4 in Fig. 3.

Fig. 5 is similar to Fig. 2, but showing a sectional die, as a modified form of Fig. 2.

Fig. 6 is a top view of Fig. 5.

In the drawings, the numeral 10 indicates

2

generally a preferred embodiment of this invention shown in the form of an electric pressing iron. This consists of a casing 11, which is a rectangular or other suitably shaped receptacle positioned inverted and housing electric heating elements (not shown) to be supplied with a current supply at 12. The casing has an upwardly extending handle 13 therefrom, and is provided with a suitable bore therethrough to receive screw 14 extending upwardly from the die 15, so that the die may be mounted detachably onto the casing against the heating means by use of a nut 16.

The die 15 is a plurality of curling edges 17 of various contours, determining a convex surface 18. The die may be in one piece as shown in Fig. 2, or may be made of a plurality of abutting parts, joined by dovetail 19 if desired; the die parts as in Fig. 6, are indicated by the numerals 20, 21 and 22, respectively. Each die part will have its individual screw as 20', 21' and 22', and the casing in such instance will be provided with suitable bores 23 and 24, for the screws 20' and 22', respectively, which are for the reception of securing nuts. The die is of metal and of course becomes heated when electrical supply is connected at 12. Any other form of heated heating means may be used with a die form to suit, but always the operating surface of the die is convex or of convex section as would be the portion of the surface of a sphere or ellipsoid.

In Fig. 1 is shown a fur pelt 23 on a table 24, with the die of the device 10 on the hair side of said pelt; only two hairs 25 and 26 are shown for sake of clarity of illustration.

In operation, the die is heated by applying electric current at 12, and is positioned on a spot or area of the hair side of the pelt, which hair is to be curled. Pressure is applied on the handle and the device rocked and even at times manipulated to be given a slight turn. Varying of hand pressure and speed of die movement will control closeness of the curling of the hairs acted on by the die and the extent of curl effected. By the hand actions indicated, the curling edges 17 of the die will contact whole hairs, point by point progressively, whereby said hair will be better curled than is possible with a flat die.

This invention is capable of many forms and applications. It is therefore intended that the showing herein be deemed illustrative only and that the patent shall cover the teachings herein as set forth in the following claims.

I claim:

1. In a fur curling tool of the character de-

Scribed, a frame having a handle, an electrically operative heating means carried on the frame and a die positioned on the frame adjacent said heating means and adapted to be heated thereby; said die including a plurality of curling edges of various contours determining a convex surface to be rocked on a fur pelt upon manual movement of the device by hold on the handle; said curling edges being adapted as the device is manipulated so that the die rock on the pelt, to make sliding contact with hairs of the pelt along from point to point progressively on said hairs.

2. A fur curling device as defined in claim 1, wherein the die comprises a plurality of parts in abutment and removably mounted on the frame; each of said die parts having a component of the convex surface.

3. A fur curling device as defined in claim 1, wherein the die comprises a plurality of parts in abutment and independently removably mounted on the frame; each of the said die parts having a component of the convex surface.

SAMUEL G. SHAPIRO.
